**HOUSING FOR BLOWER, VACUUM OR SIMILAR
AIR CIRCULATING DEVICE**

Joseph A. La Barber, Kern City, Calif., assignor to
Henry Weiland, Hacienda Heights, Calif.

Filed Sept. 1, 1970, Ser. No. 24,796

Term of patent 14 years

Int. Cl. D24—99; D15—05

U.S. Cl. D83—1

FIG. 1

FIG. 2

FIG. 3

FIG. 1 is a perspective view of a housing for blower, vacuum or similar air circulating device showing my new design;

FIG. 2 is a top plan view thereof; and

FIG. 3 is a side elevational view thereof.

The broken lines are shown in FIGS. 1, 2 and 3 for illustrative purposes only.

I claim:

The ornamental design for a housing for blower, vacuum or similar air circulating device, as shown.
